W. H. BROOKS.
LOOSE SHEET BINDER.
APPLICATION FILED AUG. 20, 1914.

1,171,167.

Patented Feb. 8, 1916.

UNITED STATES PATENT OFFICE.

WILLIAM H. BROOKS, OF PHILADELPHIA, PENNSYLVANIA, ASSIGNOR TO WILLIAM F. MURPHY'S SONS CO., A CORPORATION OF PENNSYLVANIA.

LOOSE-SHEET BINDER.

1,171,167.

Specification of Letters Patent. Patented Feb. 8, 1916.

Application filed August 20, 1914. Serial No. 857,686.

To all whom it may concern:

Be it known that I, WILLIAM H. BROOKS, a citizen of the United States, residing in the city and county of Philadelphia, State of Pennsylvania, have invented a new and useful Loose-Sheet Binder, of which the following is a specification.

My invention consists of a loose sheet binder composed of separable leaves and 10 impaling pins or forks which are secured to one leaf and adapted to be passed through slots in the other leaf, said forks and slots being flat of approximately quadrilateral form, whereby a sheet or sheets impaled will 15 be held steadily and firmly on said bars and restrained in a great measure from turning or twisting thereon, and the forks are most firmly secured to the leaf and immovably sustained thereon.

20 The invention is satisfactorily illustrated in the accompanying drawing, but the important instrumentalities thereof may be varied, and so it is to be understood that the invention is not limited to the specific details shown and described.

Figure 1 represents a perspective view of 25 a loose sheet binder embodying my invention. Fig. 2 represents a transverse vertical section thereof on the line $x-x$ Fig. 1, on an enlarged scale. Figs. 3 and 4 represent transverse horizontal sections of portions on the line $y-y$ Fig. 2, certain parts being in 30 different positions in the two figures. Fig. 5 represents a longitudinal vertical section 35 of a portion on the line $z-z$ Fig. 1, on an enlarged scale. Fig. 6 represents a side elevation of an impaling pin or fork and its connected plate. Fig. 7 represents a plan view of a portion of the locking plate employed.

Similar numerals of reference indicate corresponding parts in the figures.

Referring to the drawings: 1 designates the lower leaf of a loose sheet binder, and 2 45 designates the upper leaf thereof. Fixed on what may be termed the hinged end portion of the lower leaf 1 is the transversely-extending plate 3, preferably of metal, from which rise the impaling forks 4, which are 50 quadrilateral in cross section with its edges preferably rounded, said bars being secured to said plate by heading the ends of the former to the latter as at 5, after the manner of riveting, or by other suitable means.

55 It is deemed important that the impaling

forks are arranged with their broad sides parallel to the direction of the length of the book whereby they prevent the sheets from turning on said forks.

On what may be termed the hinged end 60 portion of the leaf 2 is the transversely-extending tube 6 which is made preferably of metal and flattened, and has within the same, the sliding bar or plate 7 in which are the slots 8 of elongated quadrilateral form with their ends preferably rounded. In the upper and lower walls of the tube 6 are the slots 9 of elongated quadrilateral form with their ends preferably rounded, 65 said slots 9 registering with the slots 8, 70 the latter being longer than the width of the impaling forks 4, as most plainly shown in Fig. 4.

To one end of the plate 7 is swiveled the 75 male screw 9^x, which is fitted in the female screw 10, the latter being firmly secured in the interior of the tube 6, whereby by properly rotating said screw 9^x, motions in opposite directions may be imparted to said plate 7. The outer end 11 of said screw is 80 accessible at the adjacent end of the tube 6, it being squared for the application of the key 12, whereby the screw may be conveniently rotated for the purpose intended.

It will be noticed that the impaling forks 85 4 are adapted to pass freely through the slots 8 and 9, and that when the plate 7 is moved the end walls of the slots are brought into contact with the adjacent narrow edges of the forks, and tightened thereagainst, thus locking the hinge portions of the leaves 1 and 2, one with the other, and preventing the disconnection of either leaf from the other, it being seen that when the plate 7 is properly moved it will be released of its holding action on the forks 4. Then the leaf 2 may be removed, and sheets, 90 etc., may be placed on the leaf 2, and impaled by said forks, or sheets, etc., may be removed, it being evident that slots are formed in said sheets, etc., so that the latter 100 may be fitted on said forks and when they are in position they are prevented from turning or twisting on said forks owing to the flat sides thereof. Then the leaf 2 is 105 pressed down and the plate moved, whereby it is locked to said forks, and thus said leaf 2 may remain as a fixture on the sheets, etc., and lower leaf 1 after the manner of a 110 bound-book, and the leaves may be opened 115

and closed on their hinged portions for access to the sheets, etc., while the latter remain clamped tightly at their inner ends between the leaves 1 and 2, and said ends are 5 not liable to tear off of the forks 4. The fixed plate 3, and the tube 6 are covered with pieces of canvas, buckram or other fabric which in the present case constitutes portions of the hinges of the leaves 1 and 2, 10 to which, however, I do not limit myself.

Having thus described my invention what I claim as new and desire to secure by Letters Patent, is:—

15 A loose sheet binder composed of separate leaves having hinge portions thereon, a stationary plate of rigid material on the hinged portion of one leaf, a transversely extending tube on the hinge portion of the other

leaf, a bar slideable in said tube and having slots of elongated approximately quadrilateral form, said tube having therein opposite registering slots of elongated form, impaling forks secured to said plate and entering said tube and bar in the slots therein and flat and approximately quadrilateral in 25 cross section corresponding with said slots, and means for moving said bar endwise to impinge the end walls of the slots of the tube against the narrow edges of the forks and lock the hinge portions of said leaves 30 one with the other.

WM. H. BROOKS.
